ELECTRICAL PROTECTIVE DEVICE

Charles Adin Fox, Oakland Village, Mo., assignor
to James R. Kearney Corporation, St. Louis,
Mo., a corporation of Missouri

Application April 25, 1947, Serial No. 743,747

3 Claims. (Cl. 173—324)

1

This invention relates generally to electrical protective devices and more specifically to surge arresters adapted for use in arresting surges resulting from lightning and other causes, the predominant object of the invention being to provide such a protective device with improved shunt means whereby the conductive electrical path extending through the protective device to ground is very greatly improved so that free and unimpeded passage of high frequency surges to ground is provided for.

Fig. 1 is a side elevation of a surge arrester constructed and arranged in accordance with this invention.

Fig. 2 is a horizontal section on an enlarged scale taken on line 2—2 of Fig. 1.

Fig. 3 is an enlarged, inverted plan view of the surge arrester illustrated in Fig. 1.

In the drawings, wherein is shown for purposes of illustration, merely, one embodiment of the invention, A designates generally an electrical protective device. The particular protective device illustrated in the drawings comprises an insulator 1 of the petticoat type at the upper end of which an upper terminal 2 is suitably fixed, said upper terminal being provided with a block portion 2' which is provided with an opening formed therethrough through which an end portion of a member 3 is extended. The member 3 is secured to the block portion 2' of the upper terminal 2 by a clamping bolt 4, and said member 3 is shaped as is shown to good advantage in Fig. 1; that is to say, said member 3 includes a substantially horizontal portion 3a, a downwardly curved portion 3b, and an upwardly inclined portion 3c which projects from said downwardly curved portion 3b.

The member 3 has associated therewith an arm 5 which is secured at its lower end to a supporting element 6 that is fixed to the insulator 1 through the instrumentality of a U-bolt 6'. The arm 5 is provided with a substantially vertical portion 5a and an upwardly and outwardly inclined portion 5b and said arm is secured to the supporting element by a bolt 7, said inclined portion of said arm being spaced from the portion 3b of the member 3 to provide a gap G therebetween. The supporting element 6 has fixed thereto an upper contact arm 8, and at its lower end the insulator 1 is provided with a ground terminal 9 to which is fixed a lower contact arm 10.

The lower contact arm 10 is formed from a length of resilient wire, or rod material, which is so formed and shaped as to provide said lower contact arm with transversely spaced, spirally

2

coiled portions 11, transversely spaced portions 12 being extended from the centers of the coiled portions 11 and being projected rearwardly and said portions 12 terminating in an upwardly extended loop 13 through which the shank of a bolt 14 is extended for securing the lower contact arm 10 to the ground terminal 9. The lower contact arm 10 includes transversely spaced portions 15 which extend forwardly from the lower portions of the coiled portions 11 thereof, forward sections of said portions 15 being arranged in closely related parallelism to provide the forward portion of the lower contact arm 10. At the forward end of the lower contact arm 10 the portions 15 are bent rearwardly to provide opposed gripping portions 16, and these gripping portions are flared outwardly at their rear ends as is shown in Fig. 3, sleeves 17 and a cap 18 being employed to retain various parts of the forward portion of the lower contact arm 10 in their proper related position.

The forward portion of the upper contact arm 8 is constructed in accordance with the forward portion of the lower contact arm 10 as described above, and as shown in Fig. 3; that is to say, the wire or rod-like material of which said forward portion of said upper contact arm 8 is formed is shaped to provide said upper contact arm with opposed gripping portions 19 (one of which is shown in Fig. 1) and these opposed gripping portions 19 correspond with the gripping portions 16 of the lower contact arm 10. The upper contact arm 8 is provided with a cap 20 and a sleeve 21 which retain parts of said upper contact arm 8 in their proper related positions, and said upper contact arm includes a rear portion 22 which is secured to the supporting element 6 by the bolt 7 which serves also to secure the arm 5 to said supporting element.

The electrical protective device A includes a surge link structure 23, said surge link structure comprising a tube structure 24 from the opposite ends of which cables 25 are extended. The cables 25 are provided with tool-receiving eyes 25' at their outer ends, and said cables are arranged in electrical contact with conductive elements disposed in spaced relation within the tube structure 24 to provide a gap therein (not shown). When the protective device A is to have the surge link structure applied thereto the lower cable 25 of said surge link structure is drawn, with the aid of a suitable insulated tool, into one of the gripping portions of the lower contact arm 16. The surge link structure is then elevated with the aid of the tool and the upper cable 25 of the surge link

50 55

structure is drawn into one of the gripping portions 19 of the upper contact arm 8, and such elevation of the surge link structure elevates the outer portion of the lower contact arm 10 so as to tension the coiled portions 11 of said lower contact arm and store up force therein which tends to swing the outer portion of the lower contact arm in a downward direction.

The ground terminal 9 of the protective device A is grounded and when, in the use of said device A, a surge on the line protected by the device seeks a path to ground, it will form arcs across the air gap G (which normally keeps the line potential off of the surge link structure 23) and across the gap within said surge link structure 23, and will pass to ground by way of the lower contact arm 10 and the ground terminal 9. A follow-up power arc will be established across the gap within the tube structure of the surge link and this follow-up power arc will be extinguished within said tube structure of the surge link. If, however, the surge link fails to properly extinguish the power arc, the continuance of the arc will destroy the surge link structure by burning the tube structure thereof so that its opposite end portions are separated, and when this occurs the outer portion of the lower contact arm 10 will swing downwardly, in response to force imparted by the tensioned, spirally coiled portions 11 of said lower contact arm 10, to quickly jerk the surge link structure apart, and thereby free the protective device from ground by creating a substantial air gap which will prevent re-establishment of an arc.

Prior to the present invention, surges passing to ground in the operation of a protective device of the type designated herein by the reference character A, were required to follow the turns of the coiled portions 11 of the lower contact arm 10 of the protective device, and this produced an undesirable situation which in some cases, at least, interfered to some extent with the efficiency of the protective device and reduced the life of the surge link 23. In other words, it has been found in some cases that very high current, high frequency surges induced by lightning will not follow the turns of said coiled portions 11, and that the coiled portions offer considerable impedance to the current, thus causing a reflected wave which when imposed on the original wave resulted in a momentary current which had a tendency to burst the tubular portion of the surge link 23. This situation has been corrected in accordance with the present invention by providing a shunt structure which shunts the surges around the coiled portions 11 of the lower contact arm 10 of the protective device, and thereby provides a direct path to ground for the surges.

The shunt structure referred to comprises an element 26 which is formed from a single length of wire, or rod-like material, said element being provided with a pair of spaced, upwardly extended end portions 27 which contact with a face of the ground terminal 9. These portions 27 of the shunt element 26 are secured to the ground terminal 9 by the bolt 14 previously referred to herein as serving to secure the lower contact arm 10 to said ground terminal, there being a washer 28 interposed between the spaced portions 27 of the shunt element 26 and the upwardly extended loop 13 of the lower contact arm, and a second washer 29 being interposed between the nut 9 of the bolt 9 and said loop 13 of the lower contact arm. Extended forwardly from the lower por-

tions of the spaced portions 27 of the shunt element 26 is an elongated loop portion 30 which is interposed between and contacts at its opposite sides with lower parts of the coiled portions 11 of the lower contact arm 10. It is to be noted that the loop portion 30 of the shunt element 26 is slightly tapered from back to front and as a result said loop portion is wedged between the coiled portions 11 of the lower contact arm 10, and thus makes close electrical contact engagement with the parts of the coiled portions of the lower contact arm with which the opposed side portions of said shunt element contact.

Because of the presence of the shunt element 26 in the structure of the protective device A, it is plain that a direct path for surges is provided between the surge link 23 and the ground terminal 9 which causes the surges to by-pass the coiled portions 11 of the lower contact arm 10 and thus eliminate the difficulties heretofore encountered, as recited above, when the surges were required to follow the turns of said coiled portions. In addition to providing the shunt element 26, the protective device A may be provided with a shunt 31 between the portion 5b of the arm 5 and the upper contact arm 8, so as to provide a direct conductive path between these parts and eliminate the V-shaped conductive path which would be present in the absence of the shunt 31.

I claim:

1. The combination of an electrical cutout provided with an outgoing terminal and a lower contact arm which is connected to said outgoing terminal and is provided with transversely spaced coiled portions for providing said lower contact arm with increased resiliency, and a shunt member connected to said outgoing terminal and having a portion which is disposed between said coiled portions of said lower contact arm in contact with parts thereof for providing a conductive path directly from said lower contact arm to said outgoing terminal which by-passes said coiled portions of said lower contact arm, the portion of said shunt member which is disposed between said coiled portions of said lower contact arm being in the form of a loop.

2. The combination of an electrical cutout provided with an outgoing terminal and a lower contact arm which is connected to said outgoing terminal and is provided with transversely spaced coiled portions for providing said lower contact arm with increased resiliency, and a shunt member connected to said outgoing terminal and having a portion which is disposed between said coiled portions of said lower contact arm in contact with parts thereof for providing a conductive path directly from said lower contact arm to said outgoing terminal which by-passes said coiled portions of said lower contact arm, the portion of said shunt member which is disposed between said coiled portions of said lower contact arm being in the form of a loop of tapered elongated shape.

3. The combination of an electrical cutout provided with an outgoing terminal and a lower contact arm which is connected to said outgoing terminal and is provided with transversely spaced coiled portions for providing said lower contact arm with increased resiliency, and a shunt member connected to said outgoing terminal and having a portion which is disposed between said coiled portions of said lower contact arm in contact with parts thereof for providing a conductive path directly from said lower contact arm to said

outgoing terminal which by-passes said coiled portions of said lower contact arm, the portion of said shunt member which is disposed between said coiled portions of said lower contact arm being in the form of a loop of forwardly tapered elongated shape, and said shunt member having spaced extensions which are projected from said loop and are disposed in contact with said outgoing terminal.
